UNITED STATES PATENT OFFICE.

WESLEY F. HALL, OF MATAWAN, NEW JERSEY, ASSIGNOR TO THE HANSON & VAN WINKLE COMPANY, OF NEWARK, NEW JERSEY, A CORPORATION OF NEW JERSEY.

CONVEYER.

Application filed May 17, 1926. Serial No. 109,719.

This invention relates to conveying machines in which a transfer mechanism is employed to lift articles from one part of the conveying mechanism and deposit them on another part thereof and is more particularly applicable to transferring from one tank to another articles being electroplated.

In the electroplating art it is common practice to arrange the various dipping and electrodepositing tanks in line while on each side of the tanks or centrally over the tanks horizontal conveying means such as sprocket chains or the like are provided to move the articles longitudinally through the tanks. After reaching the end of each tank the articles must be lifted out and then lowered into the next tank. This is generally done by mechanism working in conjunction with the horizontal conveying mechanism. It is common practice to have such conveying and transfer mechanism arranged in an elevated position over the tanks supported on a structure rising from the floor or suspended from the ceiling.

It is an object of the present invention to provide a transfer apparatus that will be self contained, that will not require overhead supports, that will be rugged in construction and accurate in performance and that will reduce to a minimum the longitudinal space required for the transfer.

The invention will be best understood by a description with reference to the accompanying drawings in which

Figure 1 is a side view in partial section of the conveyer;

Figure 2 is a side of the conveyer with its parts in another position;

Figure 2' is a detail view on an enlarged scale of the ends of the transfer arms.

Figure 3 is a transverse section through the center of the transferring element of the conveyer on the line 3—3 of Figure 1;

Figures 4, 5, 6 and 7 are details of construction, Figure 7 being taken on the line 7—7 of Figure 6.

My invention will be described with reference to electroplating apparatus in which separate conveyers are employed in successive tanks, as it has especial advantages in such a construction—but its use is not limited to such arrangement.

Referring first to Figure 1, there are shown at 1 and 2 the adjacent ends of two electroplating tanks. 3 are supporting

angles upon which rests the main frame 4 of the conveyer which is mounted longitudinally over the middle of the tanks. Along the central line of the tanks are horizontal conveyer sprocket chains 5 driven by sprocket wheels 6, one of which is located at the delivery end of each tank, the tail end of the chain being guided around a curved end part 7 mounted on guide 8 which being carried by the main frame serve as a support and guide for the upper reaches of the sprocket chain, the lower reaches of the chains being supported by corresponding rails 9 also mounted on the frame. Certain of the links of the sprocket chains have propelling lugs as shown at 10 which are adapted to engage with cross-bars 11 forming cathode supports from which on each side of the central frame hangers 12 depend. The hangers 12 are adapted to support by hooks or otherwise any articles intended to be passed through the tanks. The cathode cross-rods 11 rest at their ends on cathode rails 12' connected to a source of electric supply. The sprocket wheel 6 is mounted on a shaft 13 (see Figs. 6 and 7) through the medium of a key sleeve 14. Upon the same shaft is mounted and keyed thereto a driving gear 15 which meshes with a driving pinion 16 propelled by a shaft 17 from any suitable source of power. At the junction between the tanks the conveyer frame consists of two rigid frames 18 and 19 and the ends of the shaft 13 are journalled in these two frames with the sprocket wheel 6 midway between them. Upon the shaft 13 is also mounted a crank arm 20 and keyed to the same sleeve as the sprocket wheel 6 so as to be driven directly thereby. At the end of this crank arm is a roller 21 adapted to engage with a slotted cross-head 22, separate views of which are shown in Figures 4 and 5. This cross head has an arm 23 at its upper end upon which is mounted an anti-friction roller 24 that is adapted to travel in a vertical slot 25 in frame 19 and be guided thereby. The lower end of the cross-head has two arms 26 adapted to straddle a ball bearing 27 on the shaft 13 and be guided thereby. By this means the cross-head is allowed vertical play only.

As shown in Figure 4 the cross-head has an upper flange 28 longer than a lower flange 29, these flanges being spaced apart to form a slot in which the roller 21 of the crank may

fit. The lower flange 29 is purposely made shorter than the upper flange to an extent that will allow the roller 21 on the crank to pass out of the slot when the cross-head reaches its lower position which will be when the crank arm is in line with the slot, that is to say horizontal. Lifting arms 30 and lowering arms 31 are provided in pairs as shown and are pivoted respectively at 32 and 33 on the frames 18 and 19. At a point near a pivot of these arms connecting rods 34 and 35 are pivotally connected, the other ends of these connecting rods being pivoted at 36 to a cheek piece 37 on the slotted cross-head. The outer ends of the arms 30 and 31 have fingers 38 and 39 respectively which extend outwardly at such an angle to the arms as to be substantially horizontal on their upper surfaces when the arms are in their depressed position as shown in Figure 1, and the said fingers make a right-angled cup with the adjacent outer edge of the arms. The crank arm 20, when it is rotated in a direction shown by the arrow (Figures 1 and 2), enters the slot of the cross-head as shown in Figure 1 when the crank reaches the horizontal position. A further rotation of the crank now lifts the cross-head and through the connecting rods 34 and 35 also lifts the arms 30 and 31 until the crank reaches the vertical position shown in Figure 2 at which time the fingers on the ends of the arms will have approached very close to each other as shown in Figure 2. A further movement of the crank arm will lower the cross-head and when the crank has again reached the horizontal position the arms will have been returned to the position shown in Figure 1. A further movement of the crank arm now will cause the roller 21 to pass out from the slot of the cross-head with which it will not again engage until the crank has passed through 180° of rotation. In its passage across the middle of the slot of the cross-head the roller 21 has to pass over the slot between arms 26 and to hold it rigidly in relation to the cross-head during which passage a bridge 40 pivoted at 41 on the cross-head is provided. This bridge 41 is in the nature of a latch which will allow the roller on the crank to pass over the slot between the arms 26 and yet when the cross-head descends further the latch will move to one side to allow the passage of ball bearing 27, the latch in this case taking the position shown in Figure 1.

In order to keep the cathode supporting bar 11 properly centralized I attach to it some V-shaped lugs as shown at 42 (see Figure 3) which are adapted to closely fit in between the fingers 39 on the arms 31.

The outer perimeter of the frames 18 and 19 are arched around the central pivots and have fastened to their exterior edges blocks of wood 43 which are adapted to form a guide or track over which the vertical mem-

bers 12 of the cathode supports slide when the said supports are being transferred from one tank to another.

The operation of the machine is as follows: The cathode carrier 11 resting on cathode bars 12' are pushed along by the lugs 10 on the horizontal conveyer chains 5 until they are made to over-ride the fingers 38 of the lifting arms 30. When they have been thus pushed on to the fingers 38 the machine is so timed that the crank arm 20 will cause the roller 21 to impinge at this moment on the upper flange 28 of cross-head with the result that any further motion lifts the cross-head and the arms 30 so that the cathode carrier is rapidly elevated to the position shown in Figure 2, when it is immediately over the center line between the two tanks 1 and 2. In so lifting the carrier the vertical members 12 are held steady and free from vibration by bearing against side pieces 43 preferably of wood fastened to the outer perimeter of the frames 18 and 19.

When the lifting arm 30 has arrived at its uppermost position the lowering arm 31 will also have reached its uppermost position and the cathode bar 11 which has been resting in the right-angled notch between lifting arm 30 and its finger 38 will now be lifted vertically because the arm 31 is made purposely slightly longer than the arm 30 for this reason. The cathode bar 11 now resting on the arm 31 will descend with said arm when the crank 20 in its further motion lowers the cross-head. The motion of the arm 30 is arrested just after the cathode support 11 has been dropped on to the cathode rail 12' of the next tank. The crank proceeding in its regular rotation passes now through 180° without functioning on the slotted cross-head giving the desired amount of dwell between transferring operations.

It will be seen that the mechanism is so disposed that perfectly free access is had to each side of the tank and that although the mechanism is supported from the floor it is principally located at a point between the tanks where it will least incommode operations. Moreover, it is of a construction that can be made sufficiently rigid in its stationary parts to insure accuracy of co-functioning between the various members, a point of great importance where autonomy is to be depended upon. It will further be seen that the arms 30 and 31 are moving very slowly as they approach the point where they are to make the transfer, the crank at this time moving past its dead center. By locating the pivotal points 32 and 33 beyond the central line of the tanks, the tanks or the conveyers may be placed close together and yet enable the arms 30 and 31 to give the necessary lift to the carriers to clear the tanks. From this it will be seen that the height of the lift can be quite independent

of the length of the arms or of the proximity of the tanks or conveyers.

While I have described the conveyer as especially adapted to electroplating apparatus, it is not my intention to have my claims limited to such use as it is evident that other dipping processes may be carried out by the invention and these may be cases where such a transferring mechanism may be used between conveyers without involving tanks.

I claim:—

1. In conveying mechanism, the combination comprising lifting and lowering arms journalled on substantially parallel horizontal axes, the axis of the lifting arms being spaced from that of the lowering arms so that their outer ends will describe arcs intersecting above the axes of the arms, the said arms having at their outer ends means for holding objects, and means for moving said arms simultaneously upward until their object-holding means come together, said arms being adapted to cause objects to pass from the lifting arms to the lowering arms.

2. In a conveying mechanism, the combination comprising lifting and lowering arms journalled on substantially parallel horizontal axes, the axis of the lifting arms being spaced from that of the lowering arms so that their outer ends will describe arcs intersecting above the axes of the arms, the said arms having at their outer ends means for holding objects, and means for moving said arms simultaneously upward until their object-holding means come together, said arms being adapted to cause objects to pass from the lifting arms to the lowering arms, and stationary guides adjacent the arms for steadyng articles being transferred.

3. In a conveying mechanism, the combination comprising longitudinal conveyer means, means for transferring objects from one part of the conveyer to another consisting of lifting and lowering arms journalled on substantially horizontal axes transversely to the conveyer, the axis of the lifting arms being spaced from that of the lowering arms in the direction of travel of the conveyer, the said arms having at their outer ends means for holding objects, and means for moving said arms simultaneously upward until their object-holding means come together above the conveyer, said arms being adapted to cause objects to pass from the lifting arms to the lowering arms.

4. In a conveying mechanism, the combination comprising a longitudinal conveyer, means for transferring objects from one part of the conveyer to another consisting of lifting and lowering arms journalled on substantially horizontal axes transversely to the conveyer, the axes of the arms being spaced apart from each other and at an elevation above that of the longitudinal convey-

er, the said arms having at their outer ends means for holding objects, and means for moving said arms simultaneously upward until their object-holding means come together above the conveyer, said arms being adapted to cause the objects to pass from the lifting arms to the lowering arms.

5. In a conveying apparatus, the combination comprising continuously operating longitudinal conveying mechanism, arms pivoted on a horizontal axis transverse to the conveying mechanism operated intermittently for lifting articles from one part of the conveying mechanism, other arms pivoted on an axis spaced apart horizontally from the axis of the lifting arms co-acting with said lifting arms for taking the articles from said lifting arms and lowering them on to another part of the conveying mechanism.

6. In a conveying apparatus, the combination comprising longitudinal conveying mechanism, pivoted arms for lifting articles from one part of the conveying mechanism, other pivoted arms co-acting with the lifting arms for taking the articles from said lifting arms and lowering them on to another part of the conveying mechanism, the arms and the conveying mechanism being geared together to operate the arms intermittently while the longitudinal conveying mechanism operates continuously.

7. In a conveying apparatus, the combination comprising longitudinal conveying mechanism, arms pivoted transversely of the conveying mechanism for lifting articles from one part of the conveying mechanism, and other pivoted arms co-acting with the lifting arms for taking the articles from said lifting arms and lowering them on to another part of the conveying mechanism, the arms and the conveying mechanism being geared together to operate the arms intermittently while the longitudinal conveying mechanism operates continuously, said arms being adapted to cause the transfer of the articles from the lifting to the lowering arms at the point above the conveying mechanism where the arcs of travel of the arms intersect.

8. In a conveying apparatus, the combination comprising longitudinal conveying mechanism, pivoted arms for lifting articles from one part of the conveying mechanism, other pivoted arms co-acting with the lifting arms for taking the articles from said lifting arms and lowering them on to another part of the conveying mechanism, the arms and the conveying mechanism being geared together to operate the arms intermittently while the longitudinal conveying mechanism operates continuously, the radius of the lowering arms being greater than that of the lifting arms to insure the transfer of the articles.

9. In a conveying apparatus, the combina-

tion comprising longitudinal conveying mechanism, pivoted arms for lifting articles from one part of the conveying mechanism, other pivoted arms co-acting with the lifting arms for taking the articles from said lifting arms at the point of maximum elevation and lowering them on to another part of the conveying mechanism, a vertically movable cross-head connected to the arms 10 and a crank rotated continuously by the horizontal conveying mechanism and engaging periodically with the cross-head to simultaneously lift the arms and lower them.

10. In a conveying apparatus, the combination comprising longitudinal conveying mechanism, pivoted arms for lifting articles from one part of the conveying mechanism, other pivoted arms co-acting with the lifting arms for taking the articles from said 15 lifting arms and lowering them on to another part of the conveying mechanism, a vertical movable cross-head connected to the arms and a crank rotated continuously by the horizontal conveying mechanism and 20 engaging periodically with the cross head to simultaneously lift the arms and lower them, the radius of the lowering arms being greater than the radius of the lifting arms to effect the transfer of the articles from the 25 lifting to the lowering arms when the said arms reach their highest position.

11. In conveying apparatus, the combination comprising two separate longitudinal conveyers, longitudinal rails, supports adapted to ride on said rails and be propelled 30

thereon by the conveyers, pivotal lifting arms adapted to engage with their free ends under the supports and lift them from one conveyer to a position midway the conveyers, pivotal lowering arms adapted to engage 40 with their free ends under the supports at the midway position and lower them onto the other conveyer.

12. In a conveying apparatus, the combination comprising two longitudinal conveyers, means comprising pivoted arms for lifting articles from one of the conveyers, and means comprising pivoted arms for taking the articles from said lifting means and depositing them on the other conveyer, the 45 pivots of said arms being located on each side of the middle line between the conveyers so as to permit the close approach of the conveyers without limiting the height of the 50 lift.

13. In a conveying mechanism, the combination comprising lifting and lowering arms journalled on substantially parallel horizontal axes, the axis of the lifting arms being spaced from that of the lowering arms so 55 that their outer ends will describe arcs intersecting above the axes of the arms, the said arms having at their outer ends means for holding objects, and means for moving said arms upward until their object-holding means come together, said arms being adapted to cause objects to pass from the lifting arms to the lowering arms.

WESLEY F. HALL.
